APPARATUS FOR INSTRUCTION IN THE USE
OF FIREARMS

Stanley D. Martin, Waltham, Mass.

Application December 28, 1943, Serial No. 515,916

4 Claims. (Cl. 35—25)

This invention relates to apparatus for use in instructing individuals in the proper handling and use of firearms such as rifles, shotguns, revolvers and the like.

It has been estimated that only two percent of the men entering the armed services have any knowledge of how to handle and use a rifle properly and undoubtedly it is mainly because of this almost universal lack of knowledge respecting firearms that small arms firing schools have long been in operation as an adjunct to rifle associations. However, so far as I know the fundamental principles of marksmanship have heretofore been imparted to the student largely through verbal or written instructions.

My invention has for its object to provide an apparatus for use by individuals in acquiring the knowledge and skill respecting the handling and use of firearms that are essential to good marksmanship.

It is also an object of this invention to provide an apparatus of the kind referred to by means of which a student or beginner may give himself practice in aiming and correct trigger-pulling after having acquired an understanding of the mode of using the apparatus.

To these ends I have provided an apparatus of the character described which, in its preferred form, may be constructed and used as set forth in the following description, although it is to be understood that modifications thereof are intended to be included within the scope of the appended claims by which latter the several novel features of the invention are defined.

In the accompanying drawings:

Figure 1 is a diagrammatic side elevation of an apparatus for use in instructing individuals in the use of firearms, said apparatus being constructed in accordance with this invention.

Figure 2 is a front elevation of the target forming part of the apparatus shown in Fig. 1.

Figure 3 is an enlarged side elevation, partly broken away, of the firearm forming part of the apparatus shown in Fig. 1.

Figure 4 is an end view of the muzzle of the barrel of the firearm shown in Figs. 1 and 3.

The illustrated embodiment of this invention includes a target structure that is indicated generally at 10; a firearm 11 herein shown as a rifle; an indicator-operating bare electric conductor 12 consisting of an elongate flexible strand of wire connecting the firearm 11 with target structure 10; two visual signals 13 and 14 which may, for convenience, be mounted upon the target structure 10 where they are within the range of vision of the individual using the apparatus; an indicator instrument 8 that is operated by the wire 12 and which includes a pointer 22 that is also within the range of vision of the individual using the apparatus, and certain electric circuits presently to be described.

The target structure 10 comprises a panel 15 of wood or other non-conducting material, said panel being provided with legs 16 by which it is supported in an upright position from the floor or ground facing the firearm 11.

The visual signals 13 and 14 are electric incandescent lamps provided, respectively, with a white bulb and a red bulb, the sockets of said lamps being fastened in position upon the front side of panel 15.

Directly below the two lamps the front face of panel 15 is provided with the representation of the concentric rings of a target as shown at 17, Fig. 2, and at the center or bull's-eye thereof the panel is made with a hole 18 through which wire 12 extends. From the hole 18 wire 12 passes around a metal pulley 19 and thence downwardly around a sheave 20 below which it is provided at its extremity with a weight 21. The opposite end of the wire 12 is fastened at 23 to, but insulated from, the top side of the breech of the firearm immediately in front of the rear sight 7 of the latter.

The front sight of the firearm 11 is an apertured metal member 4 herein shown as a ring welded or otherwise fastened in position upon the top side of the barrel 9 adjacent to the muzzle thereof and disposed in a plane that is perpendicular and at right angles to the axis of the barrel. As shown in the drawings the wire 12 extends through the aperture of this ring.

The sheave 20 of the target is fast upon one end of a shaft 21 journaled in a bearing secured to the rear side of panel 15. This shaft extends through the panel 15 and has fast upon its opposite front end a pointer 22 co-operatively associated with a circular dial of numbers 6 that is concentric with shaft 21 and provided upon the front face of the panel 15. It will thus be clear that endwise displacement of the firearm 11, while the latter is held in firing position with wire 12 taut, will act through said wire to rotate sheave 20 and shaft 21 thereby adjusting pointer 22 angularly relatively to dial 6. When this displacement of the firearm is in a direction toward the target the pointer 22 will be angularly adjusted in a clockwise direction and when in a direction away from the target the pointer 22 will be angularly adjusted contra-clockwise.

The pulley 19 is rotatably supported by a metal bracket 24 mounted upon the rear side of panel 15 and this bracket is connected by a conductor 25 with one of the terminals of red lamp 14 whose other terminal is connected by a conductor 26 with the positive wire of a current-supplying circuit 27.

One of the terminals of white lamp 13 is connected by a lead 28 with the conductor 26, while

the other terminal of said lamp is connected by a conductor 29 with a spring contact 30 secured to, but insulated from, the under side of the firearm 11 immediately back of the trigger 31 of the latter.

One end of a conductor 32 is electrically connected at 33 to the under side of the barrel 9 of firearm 11, while the opposite end of said conductor 32 is connected with the negative wire of circuit 27.

It will thus be clear that when the trigger 31 is pulled rearwardly it will engage spring contact 30 thereby closing the circuit through white lamp 13, said circuit being traced as follows: From the positive wire of circuit 27 through conductor 26, 15 lead 28, lamp 13, conductor 29, spring contact 30, trigger 31, the barrel 9, and wire 32 to the negative wire of circuit 27.

When, during the handling of the firearm 11, the bare conductor wire 12 contacts the front sight ring 4 a circuit is completed through the red lamp 14 which is traced as follows: From the positive wire of circuit 27 through wire 26, red lamp 14, conductor 25, bracket 24, pulley 19, wire 12, ring 4, barrel 9 and conductor 32 to the negative wire of circuit 27.

The basic principles underlying all good shooting are to let the bones of the marksman's body carry the weight of the firearm as much as possible without muscular effort; to allow the flexible muscles to absorb the shock of the recoil; to squeeze the trigger smoothly and steadily by exerting controlled pressure thereon with the forefinger without movement of other hand or arm muscles and while gripping the small of the stock firmly but not tightly, since sudden movement accompanying a jerk upon the trigger will displace the firearm endwise and laterally and move the sights out of line and cause a miss; and to avoid swaying of the firearm.

The above described apparatus is especially designed for use in practising these fundamental principles and during its use the marksman points the gun toward the target and assumes a position where the wire 12 is taut and maintains the pointer 22 upon the zero point of the dial 23 with the barrel 9 aimed at the bull's-eye of the target while he pulls the trigger. As long as the firearm is thus maintained pointed toward the bull's-eye, and until the trigger is operated, the pointer 22 will remain at zero, both lamps 13 and 14 will be extinguished, and wire 12 will occupy a position at the center of the circular front sight 4 or approximately so. Now, if the trigger 31 is operated properly this condition of the apparatus will continue to prevail with the exception that white light 13 alone will be illuminated. If, however, the trigger is operated by a jerk of the forefinger, or otherwise than as above prescribed, so as to cause endwise displacement of the firearm, this fact will be shown at the target through angular displacement of the pointer 22. Or, if through faulty operation of the trigger, or otherwise, the firearm is caused or permitted to sway laterally in any direction the contact of wire 12 with the circular front sight 4 will result in illumination of red lamp 14 and it is possible for this to occur while white lamp 13 is also illuminated. Thus, proper use of the above described apparatus by the student is possible only when the firearm is held and "fired" properly and in accordance with the principles outlined above.

The firearm 11 is herein shown as an actual service rifle which is, of course, used without ammunition, but it is to be understood that this element may be a dummy or imitation firearm. 5 Therefore, the term "firearm" as herein employed is to be interpreted accordingly.

While the apparatus is not in use wires 26 and 32 are disconnected from circuit 27.

10 The gauge and length of the flexible metal conductor 12 may be varied as desired so long as the weight 5 is effective to maintain straight and taut that portion of the conductor which connects the firearm with the target.

What I claim is:

1. An apparatus of the character described comprising a fixed upstanding target having a hole formed through the center of the bull's-eye thereof; a firearm to be held and operated by a person located in front of said target and spaced away from the latter; an indicator device supported within range of vision of said person, and indicator-operating means including an elongate flexible strand whereof one end is connected with the exterior of said firearm and the opposite end portion extends through said hole and is connected with said indicator device and through which endwise displacement of the firearm while the trigger of the latter is being actuated by said person acts to operate said indicator, said strand being coincident with the line of sight when said firearm is aimed at said bull's-eye.

35 2. An apparatus of the character described constructed in accordance with claim 1 and wherein said indicator device comprises a rotatably supported shaft, a pointer fixed to one end of said shaft and co-operatively associated with a fixed index, and means connecting the opposite end of said shaft with said flexible strand.

40 3. An apparatus of the character described constructed in accordance with claim 1 and wherein said indicator device comprises a rotatably supported shaft, a pointer carried by said shaft in front of said target, means connecting the opposite end of said shaft with said strand so that endwise movement of the latter in one direction adjusts said shaft and pointer angularly in one direction, and means for yieldingly urging said strand, said shaft and said pointer in the opposite direction.

50 4. An apparatus of the character described constructed in accordance with claim 1 and wherein said elongate strand is a metal wire conductor whereof the end that is connected with said firearm is insulated from the metal parts of the latter, and wherein said apparatus also includes two electrically operated signal instruments supported in fixed positions adjacent to said target, a normally open circuit for one of said instruments including the trigger of said firearm, said strand, and a fixed contact mounted on said firearm in position to be engaged by said trigger when the latter is operated thereby to close said circuit, and a normally open circuit for the other of said instruments including said strand, the front sight and the barrel of said firearm, said front sight being circular and surrounding, but normally out of contact with, said strand but adapted to contact the latter thereby to close said last-mentioned circuit when the muzzle of the barrel is displaced laterally while aiming the firearm.

STANLEY D. MARTIN.
